Primary Examiner — Darlington Ly(74) *Attorney, Agent, or Firm* — Best & Flanagan LLP(57) **CLAIM**

The ornamental design for a bicycle fender, as shown and described.

DESCRIPTION

FIG. 1 is a top-front-left perspective view of a bicycle fender embodying my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged cross-sectional view thereof taken along line 8-8 of FIG. 1.

The broken lines in the drawings illustrate portions of the bicycle fender that form no part of the claimed design.
